UNITED STATES PATENT OFFICE.

WILLIAM H. SLAPPEY, OF HOPEWELL, ALABAMA.

FIREPLACE ATTACHMENT.

1,111,036.

Specification of Letters Patent. Patented Sept. 22, 1914.

Application filed May 26, 1913. Serial No. 769,988.

To all whom it may concern:

Be it known that I, WILLIAM H. SLAPPEY, a citizen of the United States, residing at Hopewell, in the county of Cleburne and State of Alabama, have invented a new and useful Fireplace Attachment, of which the following is a specification.

This invention relates to a fireplace attachment and one of its objects is to provide a simple, durable and inexpensive device which can be used in connection with a grate of any type, said attachment constituting means for regulating the draft through the device so that light ashes, dust, and various objectionable gases will be caused to pass upwardly through the chimney and cannot blow into the room from the fireplace.

A further object is to provide an attachment of this character which will not interfere with the ventilation of the room in which the fireplace is located.

Another object is to provide improved means for deflecting heated air from the fireplace and into the room.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is a perspective view of the attachment. Fig. 2 is a central vertical section therethrough in position within a fireplace. Fig. 3 is a section on line A—B Fig. 2.

Referring to the figures by characters of reference 1 designates a substantially vertical back plate having feet 2 at the lower end thereof for holding the same in an upright position. The back plate 1 has transverse cleats upon the front face thereof the upper cleat 4 constituting a support for a damper plate 5, which is mounted on the cleat. An opening 6 is formed in the plate back of the damper and extending through this opening is a flexible element 7 one end of which is attached to the damper 5 while the other end has a weight 8 fastened to

it and suspended back of the plate. The lower end of the back plate 1 has an opening 11 for the passage of air to the rear of said plate. A space 11 is formed under the plate 1 and between the feet 2 so as to permit air to circulate freely under the plate. Secured on the back of the plate 1 at the upper end thereof is a plate 12 having attaching bolts 13 adapted to be seated in apertures 14. Two series of these apertures are preferably provided, one series for each bolt, and thus it will be seen that plate 12 can be adjusted upwardly or downwardly to elongate or to shorten the attachment. This plate 12 serves to hold the upper end of the plate 1 spaced from the back wall of the chimney and also to hold the back plate 1 in proper relation to the front wall of the chimney so that, the damper plate 5 will always be in proper relation to the chimney wall.

In the drawings an open fireplace has been indicated at C and a grate or basket has been indicated at D. The attachment constituting the present invention is adapted to be placed on the bottom of the fireplace and back of the grate D so that the fire brick 10 will be directly back of and above the grate and thus be contacted by the fuel. When the attachment is in place the upper end portion will extend into the chimney E at the throat thereof. The plate 12 can be adjusted along the back plate 1 so as to adapt the device for use in fireplaces of different heights. This adjustment of the plate 12 is permitted in view of the fact that it has a slot in its lower edge portion through which the weighted element 7 extends. This slot is clearly indicated in Fig. 2.

By means of the weighted element 7 the damper 5 can be shifted to any desired angle, this damper serving to deflect into the room from the open fireplace any heated air within the fireplace and above the grate and also controlling the escape of smoke, etc. Under ordinary conditions impure air, ashes and the like will be carried up through the opening in which the damper 5 is located. When, however, this damper is closed, the impure air and ashes will flow through the space 11 and passage 15, thus insuring proper ventilation in the room.

It has been found that by using this device light ashes and dust dropping to the bottom of the fireplace from the grate will be

carried off by the strong draft set up through the space 11 and up the chimney and, therefore, the scattering of ashes, etc., in the room from the fireplace is reduced to the minimum. 5 It will be apparent that by using this attachment practically two up drafts are produced, one being through the grate and between the attachment and the front wall of the chimney, while the other draft is under the grate 10 and into the passage 15 back of plate 1 and thence to the chimney, the first draft being provided for the purpose of supporting combustion while the second draft is employed to carry off the heavy gases, the light ashes 15 and the dust. It will be seen that the side edges of the plate 12 converge rearwardly (see Fig. 3) so that air spaces or passages 16 are thus produced between the side walls of the chimney and the plate 12. It will be 20 noted by referring to the drawings that the fire bricks 10 are arranged in horizontal courses, one above the other, the upper courses extending forwardly greater distances than the lower courses. Thus an 25 overhanging effect can be produced even though a vertical back plate 1 is used and, consequently, the heat will be deflected into the room more efficiently than would otherwise be the case.

30 What is claimed is:—

1. The combination with a chimney having a fireplace opening and a grate, of a vertical back plate back of the grate, courses of fire bricks supported upon the front vertical face of the back plate, the upper courses overhanging the grate, a damper 35 loosely mounted in a seat formed by the top course of inclined fire bricks and the extended upper part of the back plate, and

movable into and out of position across that portion of the chimney between the front wall thereof and the back plate, the lower end of the back plate having an opening for the passage of air to the rear of said plate and a rearwardly extending plate adjustably mounted upon the rear face of the back plate and adapted to engage the back wall of the chimney, there being openings at the sides of said rearwardly extending plate for the passage of gases entering under 50 the back plate.

2. The combination with a chimney having a fireplace opening and a grate, of a vertical back plate back of the grate, courses of fire bricks supported upon the front vertical face of the back plate, the upper courses overhanging the grate, a tiltable damper supported by the upper course and movable into and out of position across that portion of the chimney between the front wall 55 thereof and the back plate, the lower end of the back plate having an opening for the passage of air to the rear of said plate, and a rearwardly extending plate adjustably mounted upon the rear face of the back plate 60 and adapted to engage the back wall of the chimney, there being openings at the sides of said rearwardly extending plate for the passage of gases extending under the back plate.

70 In testimony that I claim the foregoing as my own, I have hereto affixed my signature in the presence of two witnesses.

WILLIAM H. SLAPPEY.
